CHARGING DEVICE

Hugh R. MacMichael, Piedmont, Calif.

Original application June 21, 1935, Serial No. 27,697. Divided and this application November 14, 1935, Serial No. 49,739. Renewed July 8, 1939.

10 Claims. (Cl. 214—26)

This invention relates to a furnace charger, especially adapted for use in charging an elongated narrow furnace of the Scotch-hearth type for lead smelting. This application is a division 5 of my co-pending application Serial No. 27,697, filed June 21, 1935.

The general object of this invention is to provide a furnace charger adaptable for serving a relatively long narrow furnace requiring at frequent time intervals fresh charge controllably and accurately deposited in a systematically arranged thin layer therein.

More specific objects are (a) to provide a moveable furnace-charger whereon charge may be placed in a thin layer with a predetermined distribution over an area generally coextensive with the charge-receiving area of the furnace; (b) to provide a charger adapted to deposit said charge in said furnace while generally reproducing therein said charger areal-distributional effect; (c) to provide a charger adapted to discharge through its bottom, but having no relatively-moving mechanical bottom parts; (d) to provide a charger of the foregoing characteristics having a plurality of spaced parallel fixed openings in the bottom part where-through the carried charge may be discharged by imparting a rapidly accelerating or decelerating movement to the charger to cause movement thereof relative to its carried charge, thereby causing the latter to be discharged by passing out through said openings; and (e) to provide operative means adapted to impart said traveling and discharge movements.

Although the novel features which are believed to be characteristic of this invention will be particularly pointed out in claims appended hereto, the invention itself, as to its objects and advantages, the mode of its operation and the manner of its organization may be better understood by referring to the following description taken in connection with the accompanying drawing forming a part thereof, in which:

Fig. 1 is a diagrammatic side elevation of a furnace and its charging system wherewith the charger of my invention may be used.

Fig. 2 is a plan of the charger.

Fig. 3 is a side elevation and partial cross section on the line 3—3 of Fig. 2.

Fig. 4 is a cross section on the line 4—4 of Fig. 3.

Like reference characters denote like parts in the several figures of the drawing.

The charger 10 has a longitudinal frame composed of the channels 12 and 13 between which

are carried a plurality of longitudinally-spaced sloping flat plates 14, the bottom of one said plate overlapping the top of the next louver fashion providing therebetween the successive spaces 15 wherethrough carried charge 16 may be forcibly discharged. Said plates 14 have a slope somewhat flatter than that of the angle of repose of the material to be handled thereby which may approximate twenty percent grade in some cases.

Said charger 10 is provided with a plurality of longitudinally spaced axles 17 having the wheels 18, and movement may be imparted thereto by means of the attached haulage rope 21 operating over the head sheave 23 and tail sheave 24, impelled by the electric winch 26 for the movement of said charger on the track 31 positioned above the level of the furnace hearth 32 and extending through the hood 33 of said furnace 34 and out under and beyond the charge feeder bins 36 and feeders 37.

Said winch 26, of a conventional type, may be driven by the reversible-controllable-variable-speed electric motor 38 provided with a conventional automatic adjustable solenoid brake 39 adapted to the deceleration of said motor and driven charger at a generally predetermined rate. The operation of said motor driven charger 10 along said track 31 may be under manual control or appropriate automatic control apparatus (not shown) may be used whereby each cycle of charging operation may be initiated by a timing apparatus and thereafter governed by positioned electrical contacts as described in my pending application Ser. No. 27,697 of June 21, 1935.

In the operation of said charging apparatus, having distributed a charge of material on the charger by means of cooperating feeders 37, the charger 10 by means of the rope 21 and winch 26 may be caused to move at a predetermined velocity towards the furnace 34, with the fixed sloping bottom plates 14 inclined downwards in the direction of charger travel. When said moving charger then reaches a predetermined position generally over said furnace, winch electric power is cut off and the brake 39 applied thereby causing a rapid deceleration at a predetermined rate such that the supported charge slides or pitches ahead relative to the decelerating charger, thereby discharging through the spaces 15.

By appropriately correlating the charger travel speed as driven by the controllable-variable-speed motor 38 and the rate of deceleration of the moving charger by means of the adjustable brake 39, and both in consideration of the charge-carrying length and slope of the 55

plates 14, the charge may be deposited in the furnace reproducing therein generally the same type of thin layer distribution as that which had existed on the charger.

- 5 The distributional effect is readily understood by analogy to manual shoveling. As examples, assume that an evenly distributed load of fluent material is placed on a shovel pallet; a skilled shoveler may then swing the shovel along a path 10 so as (a) to discharge said material into a heap, or (b) to spread it along and generally reproduce the distributional effect which prevailed on the shovel pallet, or (c) he may cause it to be spread over a much longer length than the length of 15 the shovel pallet. Or an effect intermediate to the foregoing typical examples may be produced. The charging apparatus of this invention is devised generally to duplicate any of the foregoing described depositing distributional effects from 20 the appropriately loaded charger.

The charger may be dumped by a rapid change in speed either by deceleration as specified (or by acceleration), and by causing either speed change to take place at a proper rate 25 and suitably spaced relative to the furnace position; the charger plates 14 being sloped in a direction favorable to discharging. To discharge by acceleration a substantially increased amount of power would have to be momentarily available 30 which could be provided by a larger driving motor. Or, after moving said charger to an approximate discharging position over said furnace, a compressed air cylinder arrangement may be used to provide a high-powered rapid discharging 35 acceleration and then an air-cushioned deceleration. These or other generally equivalent means for imparting a controlled movement to the charger may be provided by skilled engineers without departing from the principles of my 40 invention.

The furnace charger of my invention is peculiarly adapted to receive a proportioned distributed charge and to deposit it in a furnace reproducing therein generally the distributional 45 effect that existed on the charger. It is especially adapted to operate in the hot gases carrying abrasive dust up through the furnace hood 33, by reason of its construction without the use of relatively moving mechanical parts which 50 would be subject to wear and abrasion, and to warping by the heat of the gases.

While my charger arrangement is adapted to charge the lead hearth type of furnace, never hitherto successfully charged by mechanical 55 means, it may also be used in effecting a like transporting and discharging of materials for use other than in said furnace.

Although certain novel features of my invention have been shown and described and are 60 pointed out in the annexed claims, it will be understood that various omissions, substitutions and changes in the forms and details of the apparatus illustrated may be made by those skilled in the art without departing from the spirit of my invention.

What I claim is:

1. A charge car adapted to the carriage of fluent material comprising a load-supporting bottom having a plurality of louver-like longitudinally spaced sloping plates, overlapping with a vertical space therebetween adapted to the forced discharge therethrough of said material; a frame adapted to the substantially fixed support of said plates; and means adapted to the support of said car for travel in the direction 70 75

of slope of said plates; said car being adapted to discharge said loaded material by having imparted thereto a sudden rapid change in the velocity of said travel.

2. Charging means for an elongated furnace 5 including a charger car adapted to the handling of fluent material comprising a load-supporting bottom having a plurality of longitudinally-spaced plates positioned to provide successive open spaces between successive plates where-through said supported material may be forcibly discharged; a longitudinal frame adapted to the substantially fixed support of said plates; means adapted to the support of said car for longitudinal travel; and means adapted to impart said travel and to effect a controlled rapid change in the velocity thereof, thereby to cause a differential movement of said car relative to said carried material and thus to force the discharge of the latter. 20

3. Charging means for an elongated furnace including a charger car adapted to the handling of fluent material comprising a load-supporting bottom having a plurality of longitudinally-spaced overlapping plates positioned to provide successive open vertical spaces between successive plates where-through said supported material may be forcibly discharged; a longitudinal frame adapted to the substantially fixed support of said plates; means adapted to the support of said car for longitudinal travel; and means adapted to impart said travel and to effect a controlled rapid change in the velocity thereof, thereby to cause a differential movement of said car relative to said carried material and thus to force the discharge 25 30 35 of the latter. 35

4. Charging means for an elongated furnace including a charger car adapted to the handling of fluent material comprising a load-supporting bottom having a plurality of longitudinally-spaced longitudinally-sloping louver-like plates positioned to provide successive open vertical spaces between successive plates where-through said supported material may be forcibly discharged; a longitudinal frame adapted to the substantially fixed support of said plates; means adapted to the support of said car for longitudinal travel; and means adapted to impart said travel and to effect a controlled rapid change in the velocity thereof, thereby to cause a differential movement of said car relative to said carried material and thus to force the discharge 40 45 50 of the latter. 50

5. Charging means for an elongated furnace including a charger car adapted to the handling of fluent material comprising a load-supporting bottom having a plurality of longitudinally-spaced longitudinally-sloping louver-like overlapping plates positioned to provide successive open vertical spaces between successive plates 60 where-through said supported material may be forcibly discharged; a longitudinal frame adapted to the substantially fixed support of said plates; means adapted to the support of said car for longitudinal travel; and means adapted to impart said travel and to effect a controlled rapid change in the velocity thereof, thereby to cause a differential movement of said car relative to said carried material and thus to force the discharge 65 70 75 of the latter. 70

6. Charging means for an elongated furnace including a charger car adapted to the handling of fluent material comprising a load-supporting bottom having a plurality of longitudinally-spaced plates positioned to provide successive 75

open spaces between successive plates wherethrough said supported material may be forcibly discharged; a longitudinal frame adapted to the substantially fixed support of said plates; means 5 adapted to the support of said car for longitudinal travel; and means adapted to impart said travel and to effect a controlled rapid change in the velocity thereof, thereby to cause a differential movement of said car relative to said carried material and thus to force the discharge of the latter; said charging means being adapted 10 to receive material distributed thereover with the effect of a predetermined systematically-arranged thin layer, and being enabled suddenly 15 to discharge substantially all said carried material to an underlying furnace and generally to reproduce therein said predetermined areal distribution.

7. In apparatus for charging a furnace of the 20 character described the combination of a charge car adapted to the carriage of fluent material in a generally thin layer thereon, said car comprising a charge supporting bottom having a plurality of fixed longitudinally spaced plates to carry said charge and being provided with passage-ways in 25 said bottom between said plates wherethrough said charge may be forcibly discharged, and means connected with said charge car including a prime mover for causing reciprocal movement 30 of said car in said furnace to forcibly discharge material carried on said plates through said passage-ways.

8. Charging means for an elongated furnace including a charge car adapted to the carriage 35 of fluent material comprising a charge-support-

ing bottom for said car composed of fixed plates, adapted to carry a charge formed in a generally thin layer thereon; a plurality of fixed longitudinally spaced passage-ways in said bottom wherethrough said charge may be discharged; 5 means to impart longitudinal travel to said car at a predetermined velocity; and means to cause a rapid controlled change in said velocity of travel thereby causing the discharge of said carried charge through said spaced passage-ways. 10

9. Apparatus for charging fluent material to an elongated furnace which comprises a plurality of plates having their surfaces sloped to present material-supporting surfaces somewhat flatter than the angle of repose of the material 15 being handled, means maintaining said surfaces in substantially fixed spaced relation, said plates being arranged to define openings between said plates for discharge therethrough of material carried on said supporting surfaces, and means 20 including a prime mover for imparting reciprocal movement to said plates while maintained in said fixed spaced relation to discharge said material from said surfaces through said openings.

10. Apparatus of the character described for 25 charging a furnace which comprises a frame, a plurality of plates having material-supporting surfaces mounted on said frame, means maintaining said supporting surfaces in fixed spaced relation relative to said frame, said plates being 30 arranged to provide discharge openings between said plates and means for moving said frame in said furnace to discharge material from said surfaces through said openings.
